UNITED STATES PATENT OFFICE.

PHILIP D. PARSONS, OF SWARTHMORE, PENNSYLVANIA, ASSIGNOR TO SCOTT PAPER COMPANY, A CORPORATION OF PENNSYLVANIA.

CONVEYER, WRAPPING, AND LABELING MACHINE.

Application filed December 2, 1926. Serial No. 152,104.

My invention is directed to improvements for wrapping rolls of toilet paper with an outside protecting wrapper and which may also contain the label matter, whereby the 5 wrapping and labeling may be done in an automatic manner and with great rapidity, said improvements being embodied in a machine for conveying the rolls of toilet paper from a place or places of reception to and 10 over label or wrapper applying and pasting means such as set out in Letters Patent No. 1,570,918 and No. 1,570,919 granted to me on January 26, 1926.

In my former patents above referred to, 15 the conveying and labeling apparatus comprehended an endless conveyer chain structure having thereon lateral projections or pins upon which the rolls of toilet paper were placed and by means of which said 20 rolls were conveyed to a paste and label applying means and by reason of which the labels were caused to be wrapped about the rolls and securely fastened in an automatic manner commensurate with the speed of the 25 moving conveyer.

In the present invention, the same general character of conveyer and paste applying means is employed, but instead of a label of relatively narrow width, the wrapper employed in lieu of a separate label is made 30 sufficiently wide to project beyond each end of the roll of toilet paper, and during the conveyance of the wrapper so applied, the projecting ends of the wrapper are respectively gathered and tucked into the tubular core in an automatic manner. Moreover, 35 the conveyer is so modified that the pins which support the rolls of paper provide sufficient space between them and the conveyer chain proper to enable the wrapper to project over into the space between the roll 40 of paper and the chain conveyer to which the pins are attached.

With the above and other objects in view, 45 the nature of which will be more fully understood from the description hereinafter, the invention consists in the novel construction of conveyer, wrapping and labeling machine, as hereinafter more fully described 50 and defined in the claims.

Referring to the drawings: Fig. 1 is a side elevation of a machine embodying my improvements; Fig. 2 is a plan view of the same with part in section; Figs. 3 to 7, inclusive, illustrate the means employed for

gathering in the overlapping wrapper and tucking it within the hollow space provided by the core; and Fig. 8 is a horizontal sectional view of a portion of the conveyor with its laterally extended pins.

2 are upright frames extending from the floor and are provided with longitudinal guide bars 3 arranged in pairs and one above the other to form guideways 4. Endless conveyer chains 5 are guided in the guideways 4. The conveyer 5 is of a link belt variety and is provided at definite intervals along its length with laterally projecting pins 8, said pins having a collar 9 at a considerable distance from the chain 70 conveyer. These pins 8 are extensions of every alternate hinge pin 6 of the conveyer.

In practice, I prefer that the links of the conveyer which directly carry the pins 6 and 8 shall be connected by intermediate hinge 75 pins 10 for uniting adjacent link portions so that the conveyer may be readily guided over a sprocket wheel 16 by which it receives motion, said sprocket wheel driven by an electric or other motor 14 through the medium of suitable gearing such as the well known worm and worm wheel transmission gearing enclosed within the casing 13. The conveyer 5 may be made in any other convenient manner than that described and may 85 be driven in any other suitable manner.

The paper rolls P may be of any ordinary construction, being usually wound upon a soft cardboard core and having a diameter suitable for receiving a dispensing 90 holder. The apertures through the rolls are considerably larger than the diameter of the pins 8 of the conveyer, so that when they are placed on the pins as they travel past the roll making machines (not shown), the 95 operators place the rolls upon any unoccupied pins, no care in this respect being required.

After the roll of paper P has been placed upon the pins 8, said rolls are conveyed in 100 contact with a vertical roller 11 carried upon a lever 12 pivoted at one end and operating under a tension spring 7, so that the paper roll by contacting with the roller 11 is forced back against the collars 9 of 105 the pins 8. The paper roll so positioned then passes over and in contact with paste applying disks 17 rotating in a glue pot 17^a, and thereafter said rolls are conveyed 110 over the wrapper magazine 18 containing

the wrapper and label sheets W and adapted to be raised by a vertically adjustable support 19 having a downwardly directed shaft 20 which is automatically raised by 5 the lever 21 fulcrumed at 22 and counter-weighted at 23, whereby there is a constant tendency to move the wrappers vertically against the under portions of the rolls P in the custody of the conveyer pins. As the 10 rolls pass over the magazine, the pasted portions of said rolls pick up one end of the wrappers W whereby they are automatically wrapped about the rolls while the latter are being conveyed over and in contact with 15 said wrappers and labels. As the wrappers or labels leave the magazine, their upper portions are drawn from under a paste applying belt 49 which is mechanically driven transversely to the direction of travel of 20 the conveyer and rolls, and by reason of the application of which paste or glue the wrapper is secured in enveloping position about the roll and with the tubular ends of the wrapper projecting beyond the roll, as indicated at E, E, which projecting ends are to 25 be gathered and tucked into the tubular cores of the rolls. The particular details of the paste applying belt 49 is not shown in the present application, as the same is fully 30 described and claimed in Letters Patent No. 1,570,919 aforesaid, and to which reference may be had for a more detailed understanding of such paste applying means.

I will now describe my improvements in 35 respect to the means employed for tucking the ends of the wrappers over the rolls and into the cores. 24 is an endless sprocket chain having spaced along its length a plurality of semi-circular buckets 25 whose radius of curvature substantially corresponds to the radial distance from the center to the perimeter of the toilet paper roll when 40 covered by the wrapper, and this endless bucket conveyer is guided about a driving sprocket wheel 28 on a driving shaft 29 at 45 one end, and at the other end about a sprocket wheel 26, freely rotating upon a shaft 27 carried in upright bearings 2^a.

Arranged parallel to the bucket conveyer 50 24 is a short endless transfer bucket conveyer 33 guided about the sprocket pulley 28 at one end and about a driving sprocket wheel 30 at the other end, said sprocket wheel 30 being secured to and driven by a 55 shaft 31 which, in turn, receives its power from the main driving shaft 32 through spur gearing 34. The short bucket conveyer 33 is provided with buckets 33^a which are similar to the buckets 25 of the bucket conveyer 24. As shown, these buckets are semi-cylindrical having a curvature and radius 60 which are adapted to receive the rolls of toilet paper P when surrounded by their combined wrapper and label. As shown, the 65 transfer bucket conveyer 33 travels imme-

dately under the pins 8 and at the same surface speed, so that the rolls of toilet paper automatically pass into the buckets 33^a during their travel under the influence of the conveyer 5, and, at the same time, the bucket 70 conveyer 24 is also travelling at the same surface speed so that the buckets 25 and 33^a of the two conveyers move along side by side in unison (Fig. 2). During the period of travel of the toilet paper roll in the combined custody of the buckets 33 and pins 8, the said rolls are shifted lengthwise of the pins 8 so as to pass from the buckets 33^a into position upon the buckets 25 of the bucket conveyer 24. This is accomplished 75 by means of the obliquely arranged transfer sprocket chain 35 guided about horizontally rotating sprocket wheels 36 and 37, said sprocket chain having downwardly projecting lugs 35^a which project just sufficiently to be able to catch the rim of the toilet paper roll to push it clear of the pin 8 and from one of the buckets 33^a to one of the buckets 25, and by which latter it may then be conveyed in the direction of the arrow, 80 (Fig. 2), to the tucking mechanism T. The transfer chain 35 is driven by means of spiral gears 38 and a sprocket chain drive 39, whereby power is received from the main shaft 32. Any other suitable means for 85 driving the transfer chain may be employed, and while I prefer the transfer chain mechanism, the paper rolls may be transferred from the pins 8 into the buckets 25 90 in any other suitable manner.

Referring now to the mechanism for folding in the wrappers at each end of the roll and tucking the upper ends thereof into the hollow space within the core of the roll, the same is indicated at T in Figs. 1 and 2, and the operative mechanism therefor is also illustrated in Figs. 3 to 7, inclusive, and comprise the following instrumentalities:

The bucket conveyer shaft 27 is loosely journaled in upright frame 2^a and inside 100 from carrying the sprocket wheel 26 for the bucket conveyer 24, it also carries two disk-like frames 40 secured to the shaft and arranged respectively on opposite sides of the bucket conveyer. At intervals about these disk-like frames 40 are secured bushings 41 to which are hinged tucking arms 42, there being preferably six such tucking arms to each bushing. The tucking arms 42 are provided with specially shaped longitudinal slots 43 which are engaged by pins 44 on a sliding head 45 secured to the end of the reciprocating rod 46, said rod having lateral pins 47 moving in cam grooves 48 of the cam cylinders 50 which are firmly secured to the frames 2^a and about which the reciprocating rods 46 are caused to travel by the rotation of the shaft 27 and disk-like frames 40. The cam grooves 48 are so shaped that the rods 46 are reciprocated 105 110 115 120 125 130 135 140

during a semi-revolution thereof about the axis of the shaft 27, with the result that the pins 44 cause the tucking arms to be moved together at their free ends to gather in the 5 tubular extending wrapper about the roll P proper. The operation just described will be clearly understood from Figs. 3 to 7, inclusive, from which it will be seen that in Fig. 3, the arms are extended in a radial 10 direction and are out of contact with the tubular wrapper extension W'. As the bucket conveyer still further advances, the cam groove 48 moves the sliding head 45 slightly forward, with the result that the 15 tucking arms 42 are caused to approach each other somewhat and press upon the outside of the tubular wrapper extension W', as will be understood by reference to Fig. 4. A further advancement of the parts brings 20 a still further movement to the sliding head 45 and also a greater extent of collapsing of the tucking arms, as indicated in Fig. 5. As the parts still further advance in respect to the stationary cam 50, the tucking arms 25 become fully collapsed as indicated in Fig. 6, and finally the sliding head 45 is moved fully forward, with the result that the tucking arms are slightly spread and the plunger head 46^a forces the gathered wrapped into 30 the tubular core, as indicated in Fig. 7. It will be noted that the cam slots 43 in the tucking arms are such that said tucking arms are gradually closed for the main movement of the plunger and sliding head 45 and 35 thereafter, when the paper wrapped is gathered to a central position over the opening in the core, the tucking arms are forced slightly apart sufficiently to enable the tucking plunger to be driven forward. Thereafter, the parts return to the condition 40 shown in Fig. 3.

During these operations, the wrapper of the toilet paper roll is more or less retained in the bucket 25 by reason of the fact that 45 the tucking arms are around the gathered paper and finally the plunger enters the hole in the core, but when the said plunger is withdrawn the wrapped toilet paper roll is free to drop out of the bucket, as is indicated in the left hand part of Fig. 1.

I have described the tucking operation as applied to one end of the roll, but it will be understood from Fig. 2 that a similar operation takes place simultaneously at both ends 55 of the roll. Figs. 3 to 7, inclusive, are intended to illustrate the special features of this operation at one end of the roll, but it is to be understood that the similar operation simultaneously takes place at the other 60 end of the roll.

From the foregoing description, it will be seen that the toilet paper rolls P are received upon and conveyed by the main conveyer 5 and caused to become wrapped with a 65 wrapper which may also be the label, and

thereafter, the roll together with the tubular wrapper is suitably conveyed or transferred to a second conveyer and while in the custody therein have the tubular ends of the wrapper gathered and tucked into the tubular ends of the core, and I do not restrict myself to the particular means for transferring the rolls from the pins of the primary conveyer into the buckets or holders of the secondary conveyer, nor do I restrict 75 myself to the particular means shown for tucking in the tubular ends of the wrappers.

By printing the subject matter of the label upon the wrappers, it is manifest that the label and wrapper is applied by the same 80 operation and, therefore, reduces the cost, but it is to be understood that in such cases as where the wrapper is of very thin material, and additional label may be wrapped about the wrapper of the toilet paper roll 85 and secured in place as heretofore.

It will now be apparent that I have devised a novel and useful construction which embodies the features of advantage enumerated as desirable, and while I have in 90 the present instance shown and described the preferred embodiment thereof which has been found in practice to give satisfactory and reliable results, it is to be understood that I do not restrict myself to the details, 95 as the same are susceptible of modification in various particulars without departing from the spirit or scope of the invention.

Having now described my invention, what I claim and desire to secure by Letters Patent is:

1. A machine of the character stated, comprising an endless conveyer having lateral pins at intervals along its length adapted for carrying in suspension rolls of paper to be enclosed with encircling wrappers which extend beyond each end of the rolls, combined with a magazine for containing the wrappers and having a width greatly wider than the length of the roll, means for feeding the wrappers toward the travelling pins which pass over the magazine, means for centralizing the rolls carried by the pins when passing over the magazine whereby the wrappers extend a definite distance beyond each end of the roll, and paste applying means for cementing the wrapper about the roll while centralized therein.

2. The invention according to claim 1, wherein further, means are provided for automatically gathering in the extended ends of the wrapper on each end of the roll and tucking the same into the central aperture therein.

3. The invention according to claim 1, wherein further, means are provided for automatically gathering in the extended ends of the wrapper on each end of the roll and tucking the same into the central aperture therein, said means comprising a secondary 125

conveyer device, transferring means for delivering the rolls with their associated wrappers from the pins to the secondary conveyer device, means on opposite sides of the secondary conveyer device for gathering in the opposite ends of the wrappers and tucking them into the apertures in the rolls, and means for moving said gathering and tucking means at a speed commensurate with the speed of travel of the paper rolls and wrappers while in custody of the secondary conveyer.

4. The invention according to claim 1, wherein further, means are provided for automatically gathering in the extended ends of the wrapper on each end of the roll and tucking the same into the central aperture therein, said means comprising a bucket conveyer for supporting the paper rolls with the wrappers thereof extending on opposite sides, a short transfer conveyer coupled to travel in synchronism with the pins which carry the rolls of paper and also in synchronism with the travel of the bucket conveyer, means for discharging the rolls from

the pins and to the bucket conveyer while supported by the short transfer conveyer, and means arranged on opposite sides of the bucket conveyer for gathering in the extended wrapper portions at each end of the paper rolls.

5. The invention according to claim 1, wherein further, means are provided for automatically gathering in the extended ends of the wrapper on each end of the roll and tucking the same into the central aperture therein, said gathering and tucking means comprising a plurality of pivoted arms and operating means to cause said arms to fold together when gathering in the wrapper ends and also provided with a reciprocating plunger for forcibly pushing the gathered wrapper ends into the central aperture of the roll, and mechanical means for moving the gathering and tucking means along with the travel of the paper rolls and for reciprocating the plunger.

In testimony of which invention, I hereunto set my hand.

PHILIP D. PARSONS.
